(57) **CLAIM**

The ornamental design for a curtain rod bracket, as shown.

DESCRIPTION

FIG. 1 is a top left front-side perspective view of a curtain rod bracket in accordance with one embodiment of the invention.

FIG. 2 is a front view of the curtain rod bracket of FIG. 1.

FIG. 3 is a rear view of the curtain rod bracket of FIG. 1.

FIG. 4 is a top down view of the curtain rod bracket of FIG. 1.

FIG. 5 is a bottom up view of the curtain rod bracket of FIG. 1.

FIG. 6 is a right side view of the curtain rod bracket of FIG. 1.

FIG. 7 is a top left front-side perspective view of a curtain rod bracket in accordance with another embodiment of the invention.

FIG. 8 is a front view of the curtain rod bracket of FIG. 7.

FIG. 9 is a rear view of the curtain rod bracket of FIG. 7.

FIG. 10 is a top down view of the curtain rod bracket of FIG. 7.

FIG. 11 is a bottom up view of the curtain rod bracket of FIG. 7; and,

FIG. 12 is a right side view of the curtain rod bracket of FIG. 7.

The broken lines shown in the drawings depict portions of the curtain rod bracket and form no part of the claimed design.

1 Claim, 3 Drawing Sheets
